AQUATIC SPORT DEVICE

Ronald G. Puckett, Olathe, Kans., assignor to P. F. Kellner, doing business as Pee-Kay Aircraft Products, International Falls, Minn.

Filed Nov. 18, 1963, Ser. No. 324,452
12 Claims. (Cl. 9—310)

This invention relates to aquatic sport devices and in particular to a water ski with a seat and controls mounted thereon that allow the ski to yaw, roll and pitch as it is towed over water by a motorboat.

Water scooters and bob skis are well known in the art, but these devices are limited in function and use. Water scooters are useful merely within a single frame of reference, that is to say, they are provided with a single rudder and suitable controls that permit the device to move in a right or left hand direction solely within a horizontal plane. On the other hand, an aquatic bob ski is provided with suitable controls that allow the device to bob and skip as it is pulled over the water and to move in a left or right hand direction, but not to bank left or right. Furthermore, the construction of these devices is such that any rider or operator using the same must be highly skillful and extremely alert in manipulating such a vehicle or else he will cause injury not only to himself but to the vehicle which he is riding.

Accordingly, it is an object of this invention to provide a water vehicle device equipped with suitable controls that allow said vehicle to move over the water while being towed in any manner that may be desirable to a rider operating said vehicle.

It is another object of this invention to provide a water ski vehicle equipped with a towline hitch that will release the towline if the operator falls from the vehicle.

Yet another object of this invention is to provide controls on a water ski vehicle that will allow movement within a single, dual or triple frame of reference.

Yet another object of this invention is to provide a water ski vehicle device that is equipped with both foot and hand manipulated controls for steering said vehicle as it is towed over the water.

Finally, it is an object of the present invention to provide an aquatic sport device, for towing over water, that is simple in construction and inexpensive to manufacture.

These and other objects of this invention will become readily apparent by reference to the following specification and drawings in which:

FIGURE 1 is a top plan view of the device;

FIGURE 2 is a side elevational view of the device;

FIGURE 3 is an end view, partly in section, taken on line 3—3 of FIGURE 2;

FIGURE 4 is an enlarged partial sectional view taken from the top half of FIGURE 2 showing the hand operated controls of the device; and

FIGURE 5 is a top sectional view taken on the line 5—5 of FIGURE 4.

Construction

Referring now to the drawings by character, and in particular to FIGURES 1 and 2, there is shown a conventional water ski 10 provided with a frame 12, foot operated controls 14, and hand manipulated controls 16. Preferably frame 12 is located at the approximate horizontal and transverse center of ski 10 so as to give the entire device suitable balance as it is towed over the water. Frame 12, which may preferably be constructed of wood or any other suitable and substantially rigid, light weight, and buoyant material, is comprised of two substantially vertically upright sections 18 and 20 secured together by a pair of cross pieces 22 and 23. In this instance, screws 24 are used to secure cross pieces 22

2

and 23 to vertical uprights 18 and 20. A seat 26 is mounted at the upper end of upright 20. Seat 26 may be adjustably mounted for vertical or horizontal movement if such is desired. A hook 28 is secured to vertical upright 18 at the approximate vertical midpoint thereof for releasable engagement with a tow line 30 by which a motor boat, not shown, pulls the entire device over the water.

Foot operated control 14 is comprised of a rudder control bar 32, control rods 34 and 35 and a rudder horn 36. Rudder bar 32 is mounted for pivotal movement about a vertical axis by a pin 38 secured to ski 10. Preferably, rudder bar 32 and pin 38 are located directly in front of upright 18. Control rods 34 and 35 are secured, one to each side, of rudder bar 32. These control rods extend rearwardly along either side of frame 12 and are secured to a rudder horn 36 which is also mounted for pivotal movement about a vertical axis by use of pin 40. A vertical stabilizer 42 with a rudder 44 hingedly mounted thereto, as by hinges 46, is mounted at the rear of and beneath ski 10. Pin 40 extends through ski 10 and is secured to rudder 44 in any convenient manner so as to allow rudder 44 to pivot about a vertical axis drawn through hinges 46 when rudder bar 32 is manipulated.

Referring now to FIGURES 3, 4 and 5 in particular, there is shown a hand operated control mounted to the upper portion of the upright 18. A generally U-shaped plate 48 is secured, as by screws 50, to an extension 52 of upright 18. A second U-formed plate 54 is pivotally secured to the rear of plate 48 by a pin 56. A generally inverted T-form element 58 is pivotally secured to plate 54 by a pin 60 passing through the stem thereof. A steering wheel 62 is rigidly secured to T-element 58 by a bolt 64. A pair of horizontal stabilizers 66 and 67 are mounted on opposite sides of ski 10 at the approximate center thereof by bolts 68. Elements 66 and 67 depend outwardly at an angle of approximately 45 degrees from the plane of ski 10. A pair of elevon plates 70 and 71 are secured by hinges 72 to stabilizers 66 and 67 respectively. Hinges 72 are mounted so that elevons 70 and 71 extend towards the rear of ski 10. Movement of plates 70 and 71 is controlled by a pair of elevon rods 74 and 75 secured to elevons 70 and 71 respectively and to opposite outer ends 76 and 77 of the head of T-element 58.

Operation

An operator seated on the seat 26 places his legs on either side of the frame 12 so that his feet contact rudder bar 32. In this position he is then able to grasp steering wheel 62. As the device is towed over the water, as by tow rope 30, he may steer the device in a right or left hand direction by moving rudder bar 32 with his feet. When the right side of rudder bar 32 is moved forward, this will cause rudder horn 36 to move in the same direction thereby causing rudder 44 to turn and thereby steer the device in a right hand direction. Correspondingly, if the left side of rudder bar 32 is moved forward, this will cause rudder horn 36 to move thereby turning rudder 44 so as to steer the device in a left hand direction.

To maintain one's balance as the device is towed over the water, wheel 62 is rotated in a clockwise or counter-clockwise direction, and this movement will cause one elevon plate to lower while the other rises. Therefore, the device will rotate about its line of movement in a right or left handed direction depending on whether the wheel is turned right or left. This "banking" movement may be employed with the use of rudder bar 32 in achieving a "banking" turn. At the same time, the attitude of the device can be changed by movement of steering wheel 62 about an axis through pin 60. Specifically, a down-

ward movement of wheel 62 will cause elevon plates 70 and 71 to lower, thereby raising the forward tip of ski 10. Conversely, raising the base of wheel 62 will cause plates 70 and 71 to rise also, thereby forcing the forward end of ski 10 to move downwardly.

From the foregoing description of the operation of the device, it can be seen that one or more of the controls provided may be operated at the same time if such is desirable. That is to say, rudder bar 32 may be moved back and forth to steer the device while wheel 62 is rotated and moved up and down thereby causing the device itself to rotate clockwise or counterclockwise while the forward end of the device is moved up or down. Thus I have devised a new and useful aquatic support device, for towing over the water, that is operable in three frames of references, singularly or all together.

Tow rope hook 28 serves as a safety feature of the device. That is to say, should the operator lose his balance and fall while being towed, tow rope 30 will slip off of hook 28 thereby preventing the device from being dragged through the water while at the same time preventing the operator from being hurt should he not be able to free himself from the device in normal operation, hook 28 is placed above the plane of attachment of tow rope 30 to the motor boat, as indicated by the angular position of tow rope 30 in FIG. 2, thereby assuring securance of tow rope 30, to hook 28. Should the operator fall, the invention will tip and fall, either to the right or left. In either event, at least a portion of the curved, forward end of ski 10 will enter the water, thereby causing the rear of ski 10 to move towards the motor boat. Thus, the invention will rotate about its normal, vertical axis, allowing the free end of hook 28 to point towards the motor boat and thus cause tow rope 30 to become disengaged from hook 28.

While the above description serves as a specific embodiment of this invention, it is apparent that the construction herein provided may be altered if so desired without extending beyond the scope of the invention. Accordingly, I do not wish to be limited to the above except for the scope of the appended claims.

I claim:

1. An aquatic sport device, for towing on water, comprising a ski-like runner, a frame thereupon and steering, banking and tilting controls arranged for manipulation by an operator, said frame located on the upper face of said runner, approximately centrally thereof, the width of said frame being less than that of said runner, said frame providing a seat for said operator and including a portion extending vertically upwardly and forwardly of said seat, means attached to the forward end of said frame for releasable engagement with a tow line, said steering controls comprising a rudder bar pivotally mounted centrally thereof, for quick movement in a horizontal plane by said operator, located forwardly of said frame, a rudder horn pivotally mounted rearwardly of said frame near the end of said runner, a pair of connecting rods attached to said rudder horn, and said rudder bar, for simultaneous movement thereof, a rudder plate located beneath said runner and secured to said horn, said rudder plate also hingedly secured to a vertically mounted stabilizer plate, said banking and tilting controls comprising a control wheel, mounted on the vertically extending portion of said frame, said wheel adapted for rotational movement about its center axis as well as about an axis transverse to the longitudinal median of said ski, a pair of plates mounted on either side of said runner about the mid-point thereof and depending outwardly at approximately 45° therefrom, each of said plates having an elevon plate hingedly mounted rearwardly thereof towards the rear of said runner, and a pair of banking connecting rods, one each secured to each elevon and to said control wheel, outside of a vertical medium plane of said ski.

2. An aquatic sport device, for towing on water, com-

prising a ski-like runner, a frame thereupon, and steering, banking and tilting controls arranged for manipulation by an operator, said frame located on the upper face of said runner, approximately centrally thereof, said frame 5 providing a seat for said operator and including a portion extending vertically upwardly and forwardly of said seat, said steering controls comprising a rudder bar pivotally mounted centrally thereof, for foot movement in a horizontal plane, a rudder horn pivotally mounted at the rear of said ski, means controlling horizontal rotational movement of said horn secured to said rudder bar, said horn having a vertically depending rudder plate mounted thereto, said banking and tilting controls comprising a control wheel mounted on the vertically extending portion of said frame, said wheel being rotatable about its center axis as well as about an axis transverse of the longitudinal medium of said ski, and a pair of depending plates each mounted on either side of said ski, each of said plates having an elevon plate hingedly mounted thereto adapted for up and down movement, said movement controlled by a rod connecting said plate and said wheel.

3. An aquatic sport device, for towing on water, comprising a ski-like runner, a frame thereupon, and steering, 25 banking and tilting controls arranged for manipulation by an operator, said frame providing a seat for said operator as well as a vertically extending portion mounted forwardly of said seat, said steering controls comprising a rudder bar pivotally mounted, a rudder horn, also pivotally mounted, said bar controlling the movement of said horn by use of a pair of rods connected to each, said horn having a depending rudder plate secured thereto, said banking and tilting controls comprising a control wheel, mounted on said vertically extending portion, said wheel adapted for movement about two opposed axes, and a pair of depending plates, each mounted on either side of said ski and having an elevon plate hingedly secured thereto, said elevon plate secured to said wheel by a rigid member for controlling movement 35 thereof.

4. An aquatic sport device, for towing on water, comprising a ski-line runner, a frame thereupon, and steering, banking and tilting controls arranged for manipulation by an operator seated on said frame, said steering controls including a pivotally mounted depending rudder operable by the feet of said operator, said banking and 45 tilting controls including a hand control, pivotally mounted on said frame for multi-axial movement, a pair of elevon plates, each hingedly secured to respective sides of said ski, and means connecting said wheel to each of 50 said elevon plates.

5. An aquatic sport device, for towing on water, comprising a ski-like runner, a pair of stabilizer plates, each secured to respective sides of said ski, a frame on said ski, and steering and banking controls arranged for manipulation by an operator, one said control arranged for foot 55 operation, the other of said controls arranged for hand operation, both said controls adapted for simultaneous but independent operation.

6. A device as in claim 5 wherein said steering controls comprise a pair of pivotally mounted bars, one of said bars adapted for foot manipulation, the other of said bars being arranged to move in response to said first bar, said other of said bars having a vertically depending rudder mounted thereto.

7. A device as in claim 5 wherein said banking controls are arranged to cause said ski to rotate about a longitudinal axis drawn through the median of ski and about a transverse axis 90° to said longitudinal axis.

8. A device as in claim 7 wherein said banking controls include a wheel mounted for hand manipulation about a central axis of said wheel as well as about a horizontal axis opposed 90° to said central axis, a pair of elevon plates, one hingedly mounted to each of said stabilizer plates, and arranged for up and down move-

ment, and means connecting said wheel and said elevon plates for control of said movement.

9. A device as in claim 8 wherein movement of said elevon plates in response to movement of said wheel about a horizontal axis causes said ski to rotate about said transverse axis and movement of said elevon plates in response to rotation of said wheel about its axis causes said ski to rotate about said longitudinal axis.

10. A water sport device to be towed over water comprising a water ski, a frame mounted thereon, said frame providing support for an operator seated thereupon, movable plates mounted on said ski and depending therefrom, said plates being arranged as to cause said ski to roll, pitch and yaw about an approximate central point thereof, and means to control said movable plates operable by said operator.

11. A device as in claim 10 wherein said frame is approximately centrally located on said ski, said means

comprising a steering wheel pivotally mounted on said frame, adapted for multi-directional manipulation by said operator, said wheel suitably connected to a pair of said plates for controlling said roll and pitch motion.

5 12. A device as in claim 10 wherein said yaw motion is controlled by a vertically depending rudder pivotally mounted to the rear of said ski, said means additionally comprising foot operable controls for movement of said rudder.
